ASH TRAY

Arthur Gorden Wheeler, Syracuse, N. Y., assignor
of one-third to Theodore E. Simonton, Caze-
novia, N. Y.

Application March 15, 1946, Serial No. 654,607

4 Claims. (Cl. 131—242)

1

This invention relates to improvements in ash trays.

The principal purposes of the invention are to provide an ash tray adapted for safe and convenient use by cigarette or cigar smokers; to provide an ash tray for such use which may be easily washed or otherwise cleaned; to provide an ash tray for such use which is of simple and durable construction and may be economically manufactured; to provide an ash tray for such use having two temporary disposal open sumps for receiving ashes and cigarette or cigar butts and a third normally closed final disposal sump into which ashes and butts from either or both of the open sumps may be easily discharged at will; and to provide an ash tray for such use preferably having means upon which smokers may temporarily place lighted cigarettes or cigars being smoked without danger of such lighted cigarettes or cigars falling out of the tray. The invention further includes so forming the tray, if desired, that lighted cigarettes or cigars dropped or falling into either of the upper sumps will roll into a choke channel portion of that sump and be extinguished, and also includes provision for automatically loosening butts stuck to walls of either of the upper sumps upon manipulation of the tray to dump butts and ashes from that sump into the normally closed sump.

An important specific purpose of the invention is to provide an ash tray having the features above set forth and consisting only of a main body member and a second member removably seated in the upper portion of the body member, said second member forming a part of each of the open sumps and also forming a cover for the normally closed sump, and said second member being removable to permit dumping of ashes and butts from the normally closed sump and also being oppositely tiltable at will in the body member to discharge ashes and butts from either of the open sumps into the normally closed sump.

The present application constitutes an improvement upon the ash tray described and claimed in my co-pending application, now Patent No. 2,397,394, issued March 26, 1946.

Other purposes and advantages of the invention will appear from the following detailed description and from the accompanying drawings, in which:

Figure 1 is a perspective view of an ash tray embodying the invention;

Figure 2 is a vertical transverse sectional view of the ash tray taken on line 2—2 of Figure 3;

2

Figure 3 is a vertical longitudinal sectional view of the ash tray taken on line 3—3 of Figure 2;

Figure 4 is a view similar to Figure 2 illustrating the tilting operation of the removable and tiltable member to dump ashes and butts from one of the open sumps into the normally closed sump;

Figure 5 is a perspective view of a slightly modified form of removable and tiltable member which may be employed with the body member of the ash tray disclosed in Figures 1 to 4; and

Figure 6 is a view similar to Figure 2 showing the member of Figure 5 seated in a body member 15 constructed as disclosed in Figures 1 to 4 to form with said body member a modified construction of ash tray embodying the invention.

Each of the ash trays shown consists of only two members, each formed of a suitable non-20 combustible material such as metal, glass, earthenware, porcelain or plastics, and each of such construction that it may be readily formed by molding or pressing. The ash tray shown in Figures 1 to 4 will first be described.

The main body member 10 of the ash tray has in plan a rectangular, and preferably oblong, form and has a bottom wall 11, two side walls 12 and two end walls 13 all integrally joined. Body member 10 is open at the top thereof, and the lower face of the bottom wall 11 is preferably flat as shown. The upper edge of each of the end walls and side walls extends in a convex arc from end to end of the wall to prevent a smoker from balancing a cigarette on any one of these edges.

Each end wall 13 of the open-top box-like main body member 10 has its inner side or face shaped to provide two flat and vertically disposed and laterally offset wall face portions 13^a and 13^b connected substantially medially of the depth of member 10 by a narrow upwardly facing and horizontally disposed wall surface portion or ledge 13^c. Each side wall 12 of member 10 has its inner side or face shaped to provide two flat and vertically disposed and laterally offset wall face portions 12^a and 12^b connected substantially medially of the depth of member 10

45 by an upwardly and inwardly facing inclined wall surface portion 12^c. The inclined wall surface portions 12^c slope downwardly and inwardly toward each other, and their lower or inner edges are located at the same horizontal level as that of the ledges 13^c. The surfaces 12^c are wider than surfaces 13^c for the reason hereinafter pointed out.

The removable and oppositely tilttable member 14 of the ash tray will now be described. This member is adapted to seat within the upper portion of member 10 with said member 14 resting on ledges 13^c and on the inner portions of the inclined surfaces 12^c to normally cover and seal the final disposal sump of the ash tray, said sump being defined by wall surfaces 13^b, 13^b, 12^b, 12^b and the top face of bottom wall 11 of member 10. For lightness, and to enable the cover to overlie a body of ashes and butts in the final disposal sump heaped centrally of the tray to a level higher than that of ledges 13^c and the lower edges of surfaces 12^c, the member 14 is preferably hollowed out at its under side as shown.

Member 14 is formed of one piece and of oblong shape in plan to provide a bar-like portion 15 extending longitudinally of member 14 medially of said member, two vertically disposed and flat end surfaces 16, 16 lying in the planes of the flat vertically disposed end faces 17—17 of the bar-like portion, two inclined upwardly and outwardly facing surfaces 18, 18 sloping downwardly and outwardly from the lower edges of the longitudinal side faces of portion 15, and two more steeply inclined upwardly and outwardly facing surfaces 19, 19 extending downward and outward from the lower edges of surfaces 18, 18 to the bottom of member 14. The bar-like portion 15 is transversely grooved to provide a series of grooves 20 each adapted to have seated therein the mid-length portion of a cigarette or cigar which a smoker desires to temporarily rest on the tray. Midway its ends, the portion 15 is increased in height to provide a finger-grippable rib 21 extending across portion 15.

At its bottom, the member 14 seats in member 10 entirely around member 14 by seating on the two ledges 13^c and the lower portions of the two inclined surfaces 12^c of member 10, to normally seal the final disposal sump around the rim of said sump. This normal sealing of the final disposal sump serves to prevent emission of odors from ashes and butts in said sump and also to exclude air from said sump to promptly extinguish any burning cigarette or cigar butt or other burning material (such as a burning match stem) deposited and sealed in said sump. To so normally seal the final disposal sump, the member 14 has two downwardly facing end edge surfaces 22, 22 which are horizontally disposed, in the normal assembled condition of the members 10 and 14, and seat flatly upon the ledges 13^c, 13^c, and two inclined and downwardly and outwardly facing longitudinal or side edge surfaces 23, 23 which connect with the ends of surfaces 22, 22 and, in the normal assembled condition of the members 10 and 14, extend downwardly and inwardly toward each other at the same angle as surfaces 12^c, 12^c of member 10 and seat on said surfaces 12^c, 12^c along the lower edges of said surfaces 12^c, 12^c as shown, leaving the surfaces 12^c, 12^c exposed for the major portion of the width of each surface 12^c, 12^c. As hereinbefore stated, member 14 is preferably made hollow below portion 15, its interior conformation conforming with that of its exterior conformation to provide, as shown, side walls 18^a, 19^a connected by end walls 16^a, 16^a.

In the normal assembled condition of members 10 and 14, the end walls 13 of member 10 extend higher throughout the width of the tray than any part of walls 18^a, 19^a, as shown. In the normal assembled condition of the two members, therefore, the final disposal sump in member 10 is

covered and sealed by member 14, and there are provided two open temporary disposal sumps of general trough-like form extending longitudinally of the tray at opposite sides of the cigarette or cigar rest portion 15 of member 14. Each such open sump has one of its sides formed by one wall surface 12^a and one wall surface 12^c of member 10 and its other side formed by one wall surface 18 and one wall surface 19 of member 14. The ends of the two open sumps are closed by, or formed by, wall surfaces 13^a, 13^a of member 14.

It will be noted that each of the two open sumps slopes upward in opposite directions transversely thereof from the lowest part of the sump, so that a cigarette or cigar butt rolling into the sump will come to rest with the butt extending longitudinally of the sump and partly overlying member 14 as well as one of the surfaces 12^c. It will also be noted that each open sump overlaps a different one of the two longitudinal edges of the final disposal sump with the lowest part of each open sump extending close to and along the adjacent longitudinal edge of the final disposal sump. Consequently, if member 14 is lifted vertically, any ashes or butts in both open sumps will discharge into the final disposal sump. Any butt adhering to either or both of the members 10 and 14 would be torn loose from said member or members with a rotating effect on the butt for discharge into the final disposal sump, any lifting of member 14 from its seat tending to roll the butt outwardly and upwardly on the adjacent surface 12 due to the partial normal extension of member 14 under the butt.

However, an important purpose of the present invention is to provide means whereby a cover such as member 14 for the final disposal sump may not only be lifted vertically for simultaneous discharge of material from both of the open sumps into the final disposal sump and for removal of member 14 for dumping the material from the final disposal sump, but also to provide means whereby the member 14 may be readily tilted at will transversely of the tray in either direction to discharge material from one or the other of the open sumps into the final disposal sump and, preferably, also to force any stuck butt outwardly and upwardly with a rolling motion as the member 14 begins to tilt to thereby effect release of any stuck butts from members 10 and 14. This dislodgment or release of stuck butts without touching them with the hands by merely tilting the member 14, is a desirable feature of the invention. It is well known that when a lighted and partially consumed cigar or cigarette is deposited in an ash tray, it tends after a short time to stick tightly to the tray, such sticking occurring at the wet end or at the lighted end, or both, of the deposited butt.

According to the present invention, the removable member 14 may be tilted in either direction transversely of the tray with one or the other of its longitudinal bottom edges fulcruming on the adjacent one of the surfaces 12^c of member 10 without any appreciable sliding of the fulcruming edge of member 14 transversely of the surface 12^c engaged thereby. While various means may be provided for the above purpose, such as any abutments contacting the surfaces 19, 19 near only their lower edges, the following described means illustrated in the drawings are preferred. At each corner of the member 10 of the tray a substantially triangular boss 24 is formed. The hypotenuse edge 24^a of each boss 24 extends downwardly and inwardly from the adjacent

surface 12^a to the adjacent surface 12^c, each such edge of each boss being curved at its lower end abruptly downward to form a low and preferably rounded abutment edge portion 24^b which joins the adjacent surface 12^c slightly outside of the lower or inner longitudinal edge of said surface 12^c to permit member 14 to seat in member 10 as above described with a close fit between the abutment portions 24^b of the four bosses 24.

With this arrangement, a person grasping opposite ends of rib 21 between the thumb and index finger of a hand, or by pressing or thrusting against one end of said rib, may tilt member 14 in either direction transversely of the tray. Member 14 is shown so tilted in one direction in Figure 4. It will also be obvious that, with this arrangement, when a person applies member 12 to member 10, the edges 24^a, 24^b of the bosses 24 will serve as centering guides to permit member 14 to settle by gravity (or under downward pressure) to its normal and proper assembled seated position in member 10.

In the modified form of ash tray shown in Figures 5 and 6, the main body member 10 is constructed precisely as in the form of tray illustrated in Figures 1 to 4. The removable and tiltable member 14^a of the modified tray is also constructed precisely as in the tray illustrated in Figures 1 to 4, with the exception that instead of its longitudinal side walls each consisting of two portions of different slope, each longitudinal side wall of member 14^a extends downward and outward from the rib portion 15 at a constant slope, these side walls of member 14^a being designated 25, 25 in Figures 5 and 6.

This difference between the two forms of tray affords, in the construction shown in Figures 1 to 4, a choke channel in each open sump which is not afforded in the construction shown in Figures 5 and 6. Each choke channel in the tray shown in Figures 1 to 4 is normally closed at its bottom by one of the surfaces 12^c and at its longitudinal sides by the adjacent surfaces 12^a and 19. Each such choke channel in the tray shown in Figures 1 to 4 has a width slightly greater than the diameter of the usual cigarette, if the tray is built for use by cigarette smokers. It will be obvious that the trays shown, which are of a size especially suitable for use by cigarette smokers, may be made on enlarged scale to especially adapt either tray for use by cigar smokers. The drawings show trays in full scale especially adapted for use by cigarette smokers. In Figure 4, a cigarette is diagrammatically represented in two different positions by the two circles 25 in full and in dotted lines. Each of the surfaces 12^c should be made wide enough transversely of the temporary disposal sums to permit rolling of a butt thereup until the butt is cleared by the rising edge of the member 14 when said member is tilted, as indicated in Figure 4.

Although I have thus described my invention in considerable detail in the best form of which I am aware, in accordance with the patent statutes, it will be evident that various changes and modifications may be made by those skilled in the art without departing from the spirit of my invention. Accordingly, I desire to be limited only by the prior art and the scope of the appended claims.

I claim:

1. An ash tray comprising a receptacle having extending downward therein from the top thereof a disposal well which has a bottom wall to which are joined two end walls and two side

walls, and a ridge-like member which is removably seated upright within the upper portion of said well for manual tilting of said seated member selectively on either of its side edges and against bodily horizontal endwise and sidewise movements of the seated member, said ridge-like seated member extending longitudinally between the end walls of said well and extending transversely thereof to the side walls of the well with said member closing off the lower portion of the well to provide a closed final disposal sump and dividing the remaining upper portion of the well into two temporary disposal sums arranged for bottom discharge into said final discharge sump.

2. An ash tray, as claimed in claim 1, in which the ridge-like member has extending longitudinally of the crown thereof an upstanding rib which is transversely grooved to form a rest for cigarettes, the length of said rib being such that it does not overhang the end walls of the well.

3. An ash tray comprising a main body member having therein an upwardly facing cavity which is rectangular in plan and is contracted entirely therearound below its upper end to provide at its lower end a final disposal sump for ashes and butts, which sump has an upwardly facing rim two opposite sides of which are disposed horizontally and the other two sides of which slope upwardly and outwardly from the sump, said cavity above said sump having two substantially parallel and vertical planar walls rising from the horizontally disposed sides of the sump rim and two substantially parallel and vertical planar walls connecting the aforesaid planar walls and rising from the sloping sides of the sump rim, a cover for said sump removably seated on said sump rim and rockable in the cavity on either of said sloping sides of the sump rim, said cover having two opposite substantially parallel vertical and planar walls provided with planar lower edges seated flatwise on the horizontally disposed sides of the sump rim and also having two opposite downwardly and outwardly sloping walls connecting said vertical walls and provided with upwardly and outwardly sloping lower edges seated and rockable on the sloping sides of the sump rim along the inner edges of the latter, means carried by the cover and extending upwardly therefrom between the sloping walls of said cover for manual engagement to rock the cover at will on either of the sloping rim sides of the sump, and fixed means carried by the body member to permit rocking of the cover on each of the sloping rim sides and prevent sliding of said cover upward on said rim sides, said cover and portions of the cavity above the final disposal sump providing two open temporary disposal sums adapted for discharge of contents of different ones of said temporary sums into the final disposal sump by rocking the cover on either of the sloping sides of the rim of the final disposal sump.

4. An ash tray comprising a body having within its outer confines two opposed and substantially planar upwardly facing surfaces of substantially equal width sloping downward and inward toward each other, a transversely grooved rest for cigarettes or the like located between the higher edges of said sloping surfaces and extending longitudinally of said edges, and a liftably removable cover wall member for said body fixed to and pendent from said rest, said cover wall member having sides sloping, in opposite directions downwardly and outwardly from said rest within the outer confines of the body to said sloping surfaces of

the body below the higher edges of said sloping body surfaces and normally forming with said body a closed sump and two open and substantially parallel sumps each above said closed sump, said body being shaped at its upper end to receive said cover wall member therewithin with said body extending upwardly at least substantially as high as the highest parts of said sloping surfaces of the body and said cover wall, said cover wall being separably engaged with said body for lifting of the member from the body and also for tilting of the member at will on either of said sloping surfaces of the body to raise one side of the member from the other one of said sloping

surfaces, and said body having means engageable with said cover wall member to prevent sliding of said member up said sloping surfaces.
